(57) **CLAIM**

The ornamental design for a “wireless communication adapter for game machine,” as shown and described.

DESCRIPTION

FIG. 1 is a top plan view of a wireless communication adapter for game machine;

FIG. 2 is a front elevational view thereof;

FIG. 3 is a bottom plan view thereof;

FIG. 4 is a rear elevational view thereof;

FIG. 5 is a right side elevational view thereof, the left side is a mirror image thereof;

FIG. 6 is a top, front and left side perspective view thereof; and,

FIG. 7 is a bottom, rear and left side perspective view.
